UNITED STATES PATENT OFFICE.

JOSEPH B. STRAUSS, OF CHICAGO, ILLINOIS.

BRIDGE.

1,150,975.

Specification of Letters Patent. Patented Aug. 24, 1915.

Application filed December 8, 1908. Serial No. 466,464.

To all whom it may concern:

Be it known that I, JOSEPH B. STRAUSS, a citizen of the United States, residing at Chicago, in the county of Cook and State of Illinois, have invented certain new and useful improvements in Bridges, of which the following is a specification.

My invention relates to bridges, and has for its object to provide a new and improved bridge of the type having a lifting counterweighted span.

Referring to the accompanying drawings, Figure 1 is a view showing one form of the bridge; Fig. 2 is a plan view of the bridge shown in Fig. 1; Fig. 3 is a section view taken on line 3—3 of Fig. 2.

Like numerals refer to like parts throughout the several figures.

Referring to Figs. 1 and 2, I have shown a moving span 1 mounted upon suitable pivots or trunnions 2. The moving span is mounted upon a support associated with the fixed span 3. A separate lifting cradling truss 4 is connected with the moving span for applying power to it. This lifting truss is shown in outline in Fig. 3 and has connected therewith the rack 5 which is engaged by the gear 6 to which the power is applied. This lifting truss is a short truss and its side members are substantially parallel to the trusses of the moving span and adjacent thereto, a portion of the truss overlapping a portion of the moving span and making connection with the moving span by means of cross girders which engage the moving span, so that as the lifting truss is moved the moving span moves with it, both the moving span and the lifting span being mounted upon the same pivots or trunnions.

2. This construction is clearly seen in Fig. 2. The connection between the cradling truss and the moving span may be made in any desired manner, depending of course upon the type of bridge being built, the necessary condition being that when power is applied to the cradling truss the moving span will be moved.

In the drawings which illustrate the construction, in a diagrammatic manner, the side members of the cradling truss are parallel with the side members of the main trusses of the moving span, and the cradling truss and moving span are connected together by the girders 4^a which are connected with the side members of the cradling truss and which engage the moving span so that

when power is applied to the cradling truss the moving span will be lifted. In the particular construction shown, the girders 4^a pass under the moving span and under the side members of the cradling truss and are fastened thereto in any desired manner. A counterweight 7 is pivotally connected to the cradling truss by the links 8 and to the fixed support 9 by the links 10, said counterweight being thus applied to the moving span through the cradling truss. This construction gives a very important practical advantage in field work and very greatly facilitates the erection of the bridge. The lifting truss and moving span can be designed and built separately. In erecting the bridge, the lifting truss, which is short and light as compared to the moving span, can be completely put in place and alined on its trunnions without the necessity of handling the full weight of the moving span and after the lifting truss is in place and properly alined the moving span can then be placed in position on its trunnions, a portion thereof resting on the members of the lifting truss which connect with the moving span. This construction also permits the trusses of the main span and approach span to be placed in line with each other.

In the operation of the device the power is applied to the rear end of the lifting truss, which projects beyond the rear end of the moving span, and since the lifting truss has members which are connected with the moving span, it will be seen that the moving span will also be lifted when the lifting truss is lifted. In the structure shown the rear end of the moving span stops substantially at the trunnions.

In Fig. 1 I have shown the lifting truss broken away so as to show the end of the moving span. This end is preferably inclined as shown, so that the end of the bottom chord is in front of the center of the trunnions. It will be noted that the sway bracing is omitted to permit the free passage of the counterweight.

I claim:

1. A bridge, comprising a moving span, a rotatably mounted cradling truss on which one end of the moving span is held, one end of said cradling truss rigidly engaging the moving span, the other end of said cradling truss projecting beyond the end of the moving span, a counterweight connected to said projecting end of said cradling truss, and

means on the cradling truss whereby power may be applied to it to lift the bridge.

2. A bridge comprising a moving span, a cradling truss connected with the moving span said cradling truss having side members, the side members of said cradling truss rigidly connected with the moving span and being in different vertical planes from the vertical planes of the trusses of the moving span, and operating mechanism connected with the cradling truss whereby the cradling truss may be moved to move the moving span.

3. A bridge comprising a moving span, an approach span, a cradling truss having side members which overlap the side members of the moving span and the approach span, said cradling truss rigidly connected with the moving span, and a supporting device on which said cradling truss is rotatably mounted.

4. A bridge comprising a moving span having one end adapted to be moved in a curved path through a vertical plane when the bridge is opened and closed, trusses forming a part of said moving span, an approach span, trusses therefor, the trusses of the moving span and approach span being in alinement, an intermediate cradling truss having members rigidly connected with the

trusses of the moving span and overlapping the trusses of the moving span and the approach span, and means for rotatably supporting said cradling truss.

5. A bridge comprising a moving span, 35 trunnions upon which it is mounted, a cradling truss associated with said moving span and having a portion which overlaps a portion of the moving span, said cradling truss being mounted on the same trunnions as the 40 moving span.

6. A bridge comprising a moving span, a cradling truss connected with the moving span, a portion of said cradling truss parallel with and overlapping a portion of the 45 moving span, said cradling truss projecting beyond the end of the moving span forming a part of the operating mechanism and a part of the load carrying structure, an operating mechanism connected with the projecting end of said cradling truss for applying power to said cradling truss to move the moving span, and a counterweight connected with the projecting end of said cradling truss for counterbalancing said moving 55 span.

JOSEPH B. STRAUSS.
